Primary Examiner — Llorellys Martinez-Rivera*Assistant Examiner* — Kwabena A. Ankobiah*(74) Attorney, Agent, or Firm* — Bridgeway IP Law Group, PLLC; Jihun Kim; Hyun Woo Shin(57) **CLAIM**

The ornamental design for a case for electronic device, as shown and described.

DESCRIPTION

FIG. 1 is a front perspective view of a case for electronic device, showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the case for electronic device and form no part of the claimed design. The other broken lines showing a key ring in FIGS. 1-8 represent environmental subject matter only and form no part of the claimed design.

1 Claim, 8 Drawing Sheets(56)
